[57] CLAIM

The ornamental design for a contact lens applicator and remover, as shown and described.

DESCRIPTION

FIG. 1 is a perspective view of the present invention with the lower end thereof mounted within the accompanying base support.

FIG. 2 is a side view of the present invention mounted within the base support, all sides being identical.

FIG. 3 is a top view of the present invention depicting the contact lens applicator portion.

FIG. 4 is a perspective view of the base support.

FIG. 5 is a perspective view of the device, detached from the base support; and,

FIG. 6 is a top view of the base support.

In FIGS. 4-6 the elements are shown separately for ease of illustration only.
